LOUIS STARK, OF BROOKLYN, NEW YORK, ASSIGNOR TO KASTER SPECIALTY MANUFACTURING COMPANY, INC., OF NEW YORK, N. Y., A CORPORATION OF NEW YORK

ANTIRATTLING DEVICE FOR DOORS AND THE LIKE

Application filed August 15, 1929. Serial No. 386,181.

This invention relates to anti-rattling devices for doors and the like and has especial reference to use with automobile doors which are subject to unusual strains and vibrations and displacements.

The main object of the invention is to provide a simple, compact, durable, economically manufactured device which can be readily attached to a door preferably adjacent the door hinge without necessitating any change in the construction and arrangement of the parts and utilizing one of the screws of the hinge, thus avoiding extra fastening means.

Further and more specific objects, features, and advantages will more clearly appear from the detailed description given below when taken in connection with the accompanying drawings which form part of the specification and which illustrate one embodiment of the invention.

Generally speaking, the invention comprises a resilient means attachable to a door or jamb and capable of counteracting and taking up the major vibrations and displacements of the door, in combination with a cushioning element associated therewith to take up and counteract minor vibrations.

Preferably, the particular form employed constitutes a bowed spring member and a rubber or resilient cushion centrally seated thereon. The device is apertured to receive an ordinary hinge screw so that the same screw that holds the hinge plate to the door or jamb can hold the anti-rattling device.

The present preferred form of the invention is illustrated in the drawings of which,

Fig. 1 is a perspective view of a door and jamb with the anti-rattling device in position;

Fig. 2 is a front elevation of the device;

Fig. 3 is a longitudinal section taken on the line 3—3 of Fig. 2;

Fig. 4 is a front elevation of a modified form of the invention;

Fig. 5 is a longitudinal section taken on the line 5—5 of Fig. 4; and,

Fig. 6 is a partial enlarged section of the form shown in Fig. 4.

As illustrated in the drawings, the present preferred form of the invention, com-

prises a bowed leaf spring element which has bowed end portions 11 and 10 and central base or seat portion 12, which has an aperture 13 therein to receive the head of a screw 14 which is one of the screws used to fasten the hinge plate 15 to the door 16 or the jamb 17.

Preferably centrally disposed on the central seat portion of the spring element is a cushioning member preferably a rubber pad 18 which in the form shown is preferably moulded to the spring element and has a central aperture in line with the aperture 13 in the spring element. This central aperture is numbered 19. The seat portion 12 is provided with spaced holes such as 20 and 21 into which the rubber of the pad 18 flows as the pad is being moulded to the spring element and aids in locking the pad to the spring element.

It will be seen from Figs. 1 and 3 that the central aperture 19 when the parts are assembled will make the pad 18 more flexible and that when the door is shut the face of the door will press against the face of the pad 18 and will trap some air in the aperture 19 and that this will act as an air cushion to additionally cushion the door.

It will be apparent that when the device is mounted as shown in Fig. 1, the ends 10 and 11 of the spring element will first contact with the adjacent edge of the jamb or door 17 when it is swung into closed position with respect to the other member 16 and thus will take up the major shocks or displacements resident in the construction and that when the door is fully closed or almost so, the cushioning pad 18 will then come into play and take up and counteract the minor vibrations which occur after the door is closed and when the automobile is in motion on the road. It will be observed that the height of the pad 18 is not as great as the distance of the ends 10 and 11 of the spring element from the seat portion and that therefore it will come into contact with the door or jamb lastly. Thus there is combined in one simple compact device a construction which will counteract or eliminate both major and minor vibrations and displacements and a device which can be economically manufac-

tured and very easily and readily attached to a door without altering or disturbing the present construction thereof to any appreciable extent.

- 5 In the modification shown in Figs. 4, 5, and 6, the rubber pad 18 is attached to the spring element by having studs or headed members 22 moulded or embedded into the rubber. These studs have grooves 23 therein to receive 10 the flowing rubber and lock the studs in place. The studs further have bores 26 therein to receive screws 25 which pass through the spring element into said bores and hold the rubber pad firmly in place on the spring element. The bores are numbered 26:

15 While the invention has been described in detail and with respect to a preferred form thereof, it is to be understood that it is not limited to such forms or details since many 20 changes and modifications may be made and the invention embodied in other forms without departing from the spirit and scope of the invention in its broader aspects. Hence it is desired to cover all forms and modifications 25 coming within the language or scope of any one or more of the appended claims.

What is claimed, is,

1. An anti-rattling device for doors and the like which comprises a bowed spring 30 member with a central rubber cushion on one side of the member, said cushion and member having an aperture to receive a hinge plate screw.

2. An anti-rattling device for doors and 35 the like which comprises a flat bowed spring member with a central rubber cushion on one side of the member and fastened thereto on the concave side of the spring, said cushion and member having an aperture to receive a 40 hinge plate screw, the top of the cushion being below the level of the line drawn between the ends of the bowed member when in normal position.

Signed at New York city in the county of 45 New York and State of New York this 9th day of August, A. D. 1929.

LOUIS STARK.

CERTIFICATE OF CORRECTION.

Patent No. 1,815,596.

Granted July 21, 1931, to

LOUIS STARK.

It is hereby certified that the name of the assignee in the above numbered patent was erroneously written and printed as "Kaster Specialty Manufacturing Company, Inc.", whereas said name should have been written and printed as Kastar Specialty Manufacturing Company, Inc., as shown by the records of assignments in this office; and that the said Letters Patent should be read with this correction therein that the same may conform to the record of the case in the Patent Office.

Signed and sealed this 22nd day of September, A. D. 1931.
